UNITED STATES PATENT OFFICE

CLIFFORD G. OAKLEY, OF NORFOLK, VIRGINIA

SHEET HOLDER FOR BEDS

Application filed January 10, 1930. Serial No. 419,923.

This invention appertains to new and useful improvements in holding devices for bed clothing, and more particularly to a novel sheet retaining means.

5 The principal object of this invention is to provide means for retaining sheets secured over the mattress in the proper manner.

Another important object of the invention is to provide means for securing short 10 sheets properly over a mattress so that when the sheet is employed as a covering, the same will not pull loose at the foot of the bed.

These and numerous other important objects and advantages of the invention will 15 become more apparent to the reader after considering the invention has described and claimed hereinafter.

In the drawings:

Figure 1 represents a fragmentary plan 20 view of the preferred form of the invention.

Fig. 2 is a sectional view of the preferred form of the invention taken substantially on the line 2-2 of Fig. 1.

Fig. 3 is a fragmentary plan view showing 25 a modification of the present invention.

Fig. 4 represents an edge elevation of the modification of that shown in Fig. 3.

Fig. 5 is a fragmentary side elevation of a 30 mattress with the form of the invention shown in Fig. 3, and 4 employed in conjunction with a sheet superimposed thereon.

Fig. 6 represents a fragmentary plan view 35 of a second modification of the invention.

Fig. 7 is an enlarged sectional view of the form of the invention shown in Fig. 6.

Referring to the drawings, wherein like numerals designate like parts, it will be seen that the preferred form of the invention includes a strip 5 secured to the foot edge of each of a pair of sheets 6-6 and these strips 5 are provided with registering buttonholes 7. This form of the invention further includes a double ply strip 8 between the plies 45 of which a longitudinally extending reinforcing or stiffening element 9 is interposed, with buttonholes through said double ply strip to which sheets or other covering may be attached by linked buttons at predetermined spaced intervals and for disposition

through the buttonholes 7 in the manner substantially shown in Fig. 2.

The strip 8 is also provided at spaced intervals with grommets 11 through which tie elements 12 are passed for connecting the 55 coiled spring 13 to the strip in the manner clearly shown in Figs. 1 and 2. The opposite end of each spring 13 has a snap hook 14 connected thereto, (see Fig. 2).

In Figure 3 the sheets 5'-5' have their 60 foot edges folded backwardly as at 6' and stitched together as at 7'. The joined edge portions of the sheet are provided with buttonholes 8'. The invention further consists in the provision of an elongated strip of material 9' which has a hem 10' at one end thereof, and to this end is secured a plurality of buttons 11' for engagement through the button holes 8' in the manner clearly shown 65 in Figs. 3 and 4.

The strip 9' is provided at its opposite 70 longitudinal edge with grommets 12' and by disposing tie strings 13' through these grommets and tying the same to the springs 14' of the bed structure generally referred to by 75 numeral 15, after the buttons 11' are disposed between the button holes 8', the sheets 5'-5' will be securely retained against displacement, at the foot end.

Figure 6 represents a second modification 80 of the invention and numerals 5a-5a represent the two sheets. These sheets are clasped together as at 6a. Connectors generally referred to by numeral 8a are provided for connecting this end portion 6a of the sheets 85 5a-5a to a strip 9a of the present invention. This strip 9a has an elastic band 10a extending therefrom and at equal spaced intervals and this strap 10a, is disposed through loops 11a-12a to permit the same to be varied in 90 length to meet existing conditions. The loop 12a has a tap 13a projecting therefrom and a separable fastener 14a is carried therefor for engagement with the hem 6a in the manner shown in Fig. 6.

The strip 9a is of multiple ply material 95 and is provided with a suitable number of grommets 15a. The end bar 16 of the spring frame of the bed structure has a plurality of bodies 17 attached thereto and equipped 100

with the pivotally mounted and ovate shaped knob 18.

As is shown in Fig. 6, the grommets 15a are provided with ovate-shaped openings 19 and by disposing the knob 18 in a position with their longitudinal axis at right angles to the longitudinal axis of the corresponding slots 19, the strips 9a will be securely fastened to the frame piece 16, or to the mattress.

10 It will thus be seen that by the use of any one of these forms of the invention, the sheets of a bed may be securely retained against displacement. Obviously, various changes in the shape, size, and materials may 15 be resorted to in the construction of this novel retaining device without departing from the spirit and scope of the invention as claimed hereinafter.

Having thus described my invention, what 20 I claim as new is:—

25 A sheet holder for beds comprising an elongated strip of flexible material, designed to be folded on itself and stitched, thereby forming an elongated pocket, buttons spaced longitudinally on the opposite faces of the strip and adjacent one edge thereof, grommets spaced longitudinally on the remaining edge, a reinforcing member extending through the pocket and positioned intermediate said buttons and grommet members, said buttons adapted to engage suitable button holes in a pair of sheets, and said grommets adapted to engage suitable fastening means for attaching the strip to a bed or mattress.

30 35 In testimony whereof I affix my signature.
CLIFFORD G. OKEY.
